DESIGN FOR A COMBINATION HANDBAG AND DOLL HOLDER

Louis Schumacher, Brooklyn, N. Y.

Application April 25, 1938, Serial No. 76,741

Term of patent 14 years

To all whom it may concern:

Be it known that I, Louis Schumacher, a citizen of the United States and resident of New York city (Borough of Brooklyn), in the county of Kings and State of New York, have invented a new, original, and ornamental Design for a Combination Handbag and Doll Holder, of which the following is a specification, reference being had to the accompanying drawing, forming a part thereof, and of which Figure 1 is an isometric view in open position of a combination handbag and doll holder showing my new design, Fig. 2 is a sectional view thereof on the line 2—2 of Fig. 1, and Fig. 3 is an isometric view thereof in closed position.

The characteristic features of the design reside in the combination of a handbag with a doll holder located within the handbag at one side and near the upper portion thereof, as shown.

I claim:

The ornamental design for a combination handbag and doll holder, substantially as shown and described.

LOUIS SCHUMACHER.
